UNITED STATES PATENT OFFICE.

DANIEL OSCAR HULL, OF CLYDE, OHIO.

ALTERNATING-CURRENT REGULATOR.

SPECIFICATION forming part of Letters Patent No. 593,050, dated November 2, 1897.

Application filed October 17, 1895. Serial No. 565,947. (No model.)

To all whom it may concern:

Be it known that I, DANIEL OSCAR HULL, a citizen of the United States, residing at Clyde, in the county of Sandusky and State 5 of Ohio, have invented certain new and useful Improvements in Apparatus for Controlling the Current in Circuits Fed from Alternating-Current Constant-Potential Mains; and I do hereby declare the following to be a 10 full, clear, and exact description of the invention, such as will enable others skilled in the art to which it appertains to make and use the same.

The object of my invention is to automatically maintain any desired current (up to 15 the capacity of the system) in a circuit which is fed from alternating-current constant (or approximately constant) potential mains, whatever be the number or resistance of the 20 translating devices which may be connected in or cut out of said circuit. These results are secured in the manner and by the means hereinafter described, and the invention is definitely pointed out in the claims.

25 In the drawings, Figure 1 is a view, partly diagrammatic, of a circuit and apparatus embodying my invention. Fig. 2 is an enlarged detail view of the switch for governing the motor which effects the desired regulation.

30 Fig. 3 is a plan view of the mechanism for operating the auto-converter brush or contact-finger. Fig. 4 is a vertical sectional view on line 4 4 of Fig. 3. Fig. 5 is a sectional view on line 5 5 of Fig. 3. Fig. 6 is a 35 horizontal sectional view on line 6 6 of Fig. 4.

Referring to the parts by letters, A A' represent the two alternating-current constant-potential mains.

40 B represents an auto-converter which is connected across said mains. The windings of the auto-converter are connected at suitable intervals with contact-plates b'. The circuit which it is desired to control has one terminal permanently connected with one 45 main A, while the other terminal is connected with the movable brush D, which may be moved into contact with any one of the contact-plates b'.

The translating devices C may be of any

desired character and may be adapted to be 50 independently connected in the circuit "in series" or cut out, as desired. It is evident that by the movement of this brush D back and forth over the contact-pieces b' any 55 desired potential difference between the terminals of the circuit to be regulated (up to the capacity of the system) can be obtained.

When the translating devices C, which may be arc-lights, are located at a distance from the controlling mechanism and are liable to 60 be severally turned on or off at any time, it is desirable to provide means which will act automatically to regulate the potential difference of the terminals and keep the current 65 constant in the circuit notwithstanding the 70 variations in resistance due to turning any number of lights on or off. The automatic movement of the brush D, as shown in the drawings, is effected by an induction-motor, and the direction in which the armature of 75 said motor moves is governed by the switch G, which switch is actuated by the core of the solenoid-magnet I, connected in the circuit to be controlled.

A particularly effective construction, combination, and arrangement of parts for automatically moving the brush D back and forth upon the small contact-pieces b' and for giving a quick make and break to the brush and contact-pieces is shown in Figs. 3 to 6. The 80 contact-pieces b' are arranged in the arc of a circle. The brush D is carried on the wheel N, mounted in the center of said arc. The wheel is a gear-wheel, which is connected by a train of gears h h' h² with the motor H. 85

The brush D is secured to the under side of a metallic bar d, and this bar is pivotally connected with the outer end of the two or more parallel bars d' d², which are in turn pivoted to the bracket n, carried by but insulated from the wheel N. This bracket n is connected by wire n³ with the main A. The bar d is always parallel with a chord which passes through these pivots of the bars d' d², which connect them with the bracket n. 90 Springs d³ engage with the middle bar d' and tend to hold it in a radial position. 95

A ring K is fixed outside of the row of con-

tact-pieces b' , and it is provided with an over-hanging flange k . On the under side of this flange are depending pins k' , which are arranged one above each of the spaces between 5 the contact-pieces b' . The outer end of the middle bar d' projects so far that when said bar is in a radial position it will enter between two adjacent pins $k' k'$, the brush D being at this time in contact with that one of the contact-pieces b' which lies between said pins. 10 When the wheel N moves in either direction, the engagement of said bar d' with one pin k' causes the bars $d' d^2$ to turn upon their pivotal connections with brackets n until the end 15 of the bar d' , being drawn inward by such movement, may pass said pin k' . The spring d^3 then swings said bars back to their normal position, and the end of the middle bar d' strikes and is stopped by the next pin k' . As 20 the said bars $d' d^2$ are moving upon their pivots to one side or the other of the radial position the brush D is drawn inward or toward the axis of the wheel. The contact between it and the contact-piece b' is not broken, however, nor is any contact made between it and any other contact-piece until the bar d' slips past the pin k' , with which it is then in contact. 25 Immediately thereafter as the arms $d' d^2$ move, as described, to the radial position the brush D is quickly carried from one contact-piece b' to the next one.

The circuit of the translating devices is divided at a point between the solenoid I and the motor II, one part of the current passing 30 over the wire j^2 , in which an inductive resistance J is connected, while the other portion passes over a wire j^3 , in which a non-inductive resistance is connected. The ends of these wires are connected with contact-pieces $g^3 g^2$, 35 which are secured to but insulated from the under side of a pivoted lever g' , and are indicated by dotted lines in Fig. 1 and shown more fully in Fig. 2. The end of this lever is 40 connected by a link i with the core of the solenoid. $g g^4$ represent curved contact-plates which lie beneath the lever g' , their ends being so close together that the space between them may be bridged by the contact-pieces $g^3 g^2$. The motor II has two field-circuits, the 45 wires $j j'$ being parts of these circuits. The first of these wires is connected with the contact-plate g , the other with the contact-plate g^4 .

When the desired current is flowing through 50 the circuit of the translating devices, the contact-pieces $g^3 g^2$ are in contact with both contact-plates $g g^4$, being held in this position by the action of the solenoid upon the lever g . Under these conditions neither of the motor field-circuits has the lead, and therefore the 55 motor does not move, but when by connecting into the circuit one or more of the translating devices or by disconnecting some of the said translating devices the current is temporarily decreased or increased the so-

lenoid-core is caused to move out of or into 65 the coil, with the result of moving the lever g' so that each of the contact-pieces $g^3 g^2$ is in contact with only one of the contact-plates $g g^4$. That one of the field-circuits which includes the non-inductive resistance gets the 70 lead of the other field-circuit, and the motor begins to move in one direction or the other, as the case may be. This causes the brush D to be moved from the contact-pieces b' in the proper direction and far enough to restore 75 the current to its normal amount.

Having described my invention, I claim—

1. In an apparatus for maintaining a constant current in a circuit fed from alternating-current constant-potential mains, in combination, an auto-converter connected across 80 said mains, a row of contact-pieces connected with the windings of said auto-converter, a movable brush adapted to contact with any of said contact-pieces, the circuit to be controlled connected at one terminal with one of the mains and at the other with said brush, an induction-motor, and a solenoid, both connected in said circuit, a reversing motor-switch connected in the circuit between the 85 solenoid and motor, mechanism connecting the movable part of said switch with the armature of said solenoid, and mechanism for transmitting motion from the motor to the converter-brush, substantially as and for the 90 purpose specified.

2. In an apparatus for maintaining a constant current in a circuit fed from alternating-current constant-potential mains, in combination, an auto-converter connected across 95 said mains, a series of contact-pieces arranged in a circular arc and connected with the windings of said converter, a gear-wheel mounted concentrically with said series of contact-pieces, a brush carried thereby and adapted 100 to contact with any of said contact-pieces, the circuit to be controlled connected at one terminal to said brush and at the other with one of the mains, an induction-motor, and a solenoid, both connected in the circuit to be 105 regulated, a train of gears connecting said motor with the brush-carrying gear and a reversing motor-switch operated by the solenoid, substantially as and for the purpose specified.

3. The combination of a series of contacts, a movable brush-carrier, two or more parallel bars pivoted thereto, a bar pivoted to all of said bars and lying parallel to a plane 110 passing through said pivots, a brush carried by said bar, a series of pins adapted to engage with one of the parallel bars, and a spring for returning said parallel bars in the described normal position, substantially as and for the purpose specified.

4. The combination of a series of contact-pieces arranged in a circular arc, a wheel pivoted at the center of said arc, a ring fixed 115

outside of said contact-pieces and having an overhanging flange, and a series of pins depending from said flange, with two or more parallel bars pivoted to and projecting out 5 from said wheel, a bar pivoted to the ends of said bars and lying parallel to a plane passing through the pivots of said parallel bars, a brush secured to the said bar, and a spring for returning said parallel bars to their nor-

mal position, substantially as and for the purpose specified.

In testimony whereof I affix my signature in presence of two witnesses.

DANIEL OSCAR HULL.
